UNITED STATES PATENT OFFICE

CHARLES W. GARRETT, OF PENN YAN, NEW YORK; MARGERY H. GARRETT EXECUTRIX
OF SAID CHARLES W. GARRETT, DECEASED

DESIGN FOR AN AERATING DEVICE

Application filed April 18, 1929. Serial No. 30,929. Term of patent 14 years.

To all whom it may concern:

Be it known that I, CHARLES W. GARRETT, residing at Penn Yan, in the county of Yates and State of New York, have invented a new, original, and ornamental Design for Aerating Device, of which the following is a specification, reference being had to the accompanying drawing, forming part thereof, in which the figure illustrated is a perspective view of the invention.

The figure discloses only one side of the aerating device, but the opposite side is substantially the same as that shown.

I claim:

The ornamental design for an aerating device, as shown and described.

CHARLES W. GARRETT.
